UNITED STATES PATENT OFFICE.

FRANK D. BEATTIE, OF SOUTH HARTFORD, NEW YORK.

CIGARETTE-MACHINE.

SPECIFICATION forming part of Letters Patent No. 700,010, dated May 13, 1902.

Application filed January 14, 1902. Serial No. 89,782. (No model.)

To all whom it may concern:

Be it known that I, FRANK D. BEATTIE, a citizen of the United States, residing at South Hartford, county of Washington, and State 5 of New York, have invented certain new and useful Improvements in Cigarette-Machines, of which the following is a specification.

The invention relates to such improvements; and it consists of the novel construction and 10 combination of parts hereinafter described and subsequently claimed.

Reference may be had to the accompanying drawings, and the reference characters marked thereon, which form a part of this 15 specification.

Similar characters refer to similar parts in both figures.

Figure 1 of the drawings is a view in perspective of my improved cigarette-machine, 20 showing the case partly opened with the filling material rolled to cylindrical form and the paper wrapper inserted in position. Fig. 2 is a cross-section of the same.

The drawings are on an enlarged scale, and 25 Fig. 2 is on a larger scale than Fig. 1.

My invention relates to hand-machines for making cigarettes.

The principal objects of the invention are to facilitate the application of the paper wrap- 30 per to the filling material and to remove from the cigarette any projecting surplus of filling material.

Referring to the drawings, my machine comprises in part a case comprising two semi- 35 cylindrical members 1 and 2, hinged together at 3 and each provided with a laterally-projecting tablet 4. Each tablet 4 is provided with a ribbon-guideway, that on the member 2 comprising a plate 5, supported a short 40 distance from the surface of the tablet, and that on the member 1 by a plate 6, in like manner supported a short distance from the surface of the tablet. A ribbon 7 is inserted between the hinged members with one end 45 projecting exteriorly through the ribbon-guideway formed by plate 5, and its other end projecting exteriorly between the guide-plate 6 and its supporting-tablet. The upper edge of each of the guide-plates 5 and 6 is 50 shown in toothed form. The inner edge of one of said plates, as the plate 6, is in like manner provided with a series of teeth 9,

which teeth are inclined toward the line of junction of the semicylindrical member 1 with its tablet 4, as shown more particularly 55 in Fig. 2.

In operating the machine the case is opened, and a supply of filling material, as tobacco, is inserted therein upon the inclosed portion of the ribbon. The case is then closed and 60 held in the hand, while the ribbon is drawn first one way and then the other until the filling material has been formed into a compact cylindrical roll, as shown in Fig. 1. A sheet of suitable wrapping-paper 10 is then 65 inserted between the guide-plate 6 and the ribbon 7 in the position shown in Figs. 1 and 2, and the ribbon drawn in a direction to cause said paper to be carried interiorly of the case. As the paper is drawn into the 70 case its inner end is deflected by the inclined toothed edge 9 of the guide-plate 6 toward the line of junction of the semicylindrical member 1 with its tablet, causing said deflected edge to be carried by the ribbon in between the ribbon and roll of filling material 75 and to accompany the ribbon in its movement around said roll. By moistening the outer edge of the paper 10 it is possible by drawing the paper wholly within the case to cause said 80 moistened edge to overlap and adhere to the first-inserted edge.

The guide-plate 6 may be of any desired form, having its inner edge inclined toward the line of junction of the semicylindrical 85 member 1 with its tablet 4.

The notched or toothed form of plate shown in Fig. 1 renders the inserted edge of the paper wrapper 10 visible, facilitating its proper alignment.

The ends of the case members may be provided with coöperating cutting mechanism, as the knife 12 on the member 1, adapted to coöperate with the edge 13 on the member 2 for the purpose of removing any projecting 95 surplusage of filling material.

The knife 12 may be brazed or otherwise secured to the member 1.

What I claim as new, and desire to secure by Letters Patent, is—

1. In a cigarette-machine, the combination with a pair of semicylindrical members hinged together, and one provided with a laterally-projecting tablet; of a guide-plate supported

a short distance from the surface of the tablet and having its inner edge portion inclined toward the line of junction of said cylindrical portion and tablet; a ribbon-guide on the other member; and a ribbon inserted between said members, and having one end projecting exteriorly through said ribbon-guide, and the other end exteriorly between said tablet and guide-plate, substantially as described.

10 2. In a cigarette-machine, the combination with a pair of semicylindrical members hinged together, and one provided with a laterally-projecting tablet; of a guide-plate supported a short distance from the surface of the tablet and having along its inner edge a series

of teeth inclined toward the line of junction of said cylindrical portion and tablet; a ribbon-guide on the other member; and a ribbon inserted between said members, and having one end projecting exteriorly through said ribbon-guide, and the other end exteriorly between said tablet and guide-plate, substantially as described. 20

In testimony whereof I have hereunto set my hand this 11th day of January, 1902.

FRANK D. BEATTIE.
